UNITED STATES PATENT OFFICE.

VIVIAN K. SPEAR, OF LYNN, MASSACHUSETTS.

IMPROVED BOOT-HEEL POLISHER.

Specification forming part of Letters Patent No. 72,105, dated December 10, 1867.

To all whom it may concern:

Be it known that I, VIVIAN K. SPEAR, of Lynn, in the county of Essex and State of Massachusetts, have invented a new and useful Improvement in Machines for Polishing the Heels of Boots and Shoes; and I do hereby declare that the following is a full, clear, and exact description thereof, reference being had to the accompanying drawings, in which—

Figure 1 is a perspective view of my machine, and Fig. 2 is a detached view of the clutch which holds the boot-heel.

A is the frame which supports the operative machinery. B is a pulley-wheel, to which the power is applied to give rotary motion to its shaft b. On the opposite end of this shaft is rigidly fixed an eccentric wheel, c, which revolves within a metal hoop or band, c', to which is attached a pitman, p, which is pivoted at its opposite end to an oscillating crank, D, which carries the polisher D'. Rotary motion being given to the shaft b, an oscillating motion is given to the crank D by means of the eccentric wheel c and the pitman p, and this oscillating motion of the crank gives the polisher a reciprocating motion in the line of an arc of a circle. The stem d, to which the polisher is attached, slides in a sleeve, s, and is pressed down by a spiral spring, s', which gives the polisher an elastic bearing on the boot-heel, and allows it to yield to the irregularities thereof.

F is the frame or rest in which the boot or shoe is suspended. This frame is mounted on a sliding base-piece, H, which allows the boot or shoe to be moved to or from the polisher, and it turns horizontally on a pivot, f. This pivot fits into a vertical sleeve or socket, e, which extends down into a slot in the base-

piece of the frame A. Said pivot f is movable vertically in said sleeve or socket, and is held in any desired position by a set-screw, the sleeve turning with the pivot f. By this means the frame F is adjustable vertically, to suit varying sizes of the boot or shoe to be operated upon.

The boot or shoe is held in the upper part of the frame F by means of a toothed plate or clutch, g, (shown in a separate figure, 2,) against which the bottom of the heel is pressed, and a screw-shaft, h, which enters a socket-hole in the top of the last, opposite the heel. Said clutch g revolves on the end of the shaft to which it is attached, and the end of the screw-shaft h enters the hole in the last loosely enough to allow the last to turn freely thereon, so that by turning the boot vertically and the frame F horizontally, all parts of the heel to be polished may be brought in contact with the polisher.

Having thus fully described my invention and its mode of operation, what I claim as new, and desire to secure by Letters Patent, is—

1. The reciprocating polisher, moving in the line of an arc of a circle by means of mechanism substantially as herein described, and having an elastic bearing, as and for the purpose set forth.

2. In combination with a reciprocating polisher, substantially as described, I claim the pivoted sliding frame to support the boot or shoe, constructed, arranged, and operating substantially as set forth.

VIVIAN K. SPEAR.
